United States Patent Office

Des. 209,435
Patented Nov. 28, 1967

209,435

DISPLAY STAND

Daniel E. Gelles, Kerhonkson, N.Y.
(1140 Broadway, New York, N.Y. 10001)

Filed Nov. 4, 1966, Ser. No. 4,553

Term of patent 14 years

(Cl. D80—10)

FIG. 1

The bottom of the stand base is plain.

I claim:

The ornamental design for a display stand, substantially as shown and described.
